EX

OR D 244

M. 244 Design C

Horace H. Hardesty
design or for a coloring book

Patented Oct. 23, 1949.

Rev. 244

Nosea H. Huntley, Cincinnati Ohio.
Letters Patent No 244 Dated Oct 23rd 1849.

The Schedule
referred to in these Letters Patent, and making part of the same.

To all whom it may concern: Be it
Known, that I, Nosea H. Huntley have invented or produced
a new combination of ornamental designs for the configuration
of Stone represented in the annexed drawings making part of this
specification, in which Fig 1. exhibits the delineation of a rec-
tangular Stone.

(a) is a door having the design (a'), a man contending with
two lions cast on and forming part of it - (b) is a door or han-
nel having the design (b') cast on and forming part of it - (c) is
a door or hannel having the design (c') cast on and forming part
of it - (d) are doors having the design (d') cast on and forming
part of each of them - (e) are the sides of the stone which together
with the back (f) have the moulding (e) laid within the leading
(e''); the same being cast on and forming part of these sides -

The stone rests upon four or more feet as represented, which
form however no part of this design -

Having thus fully described and distinctly represented the
shape or configuration, and the several ornamental designs for
theannels, sides, and doors of a cooking stone, what I claim
as new therein and desire to secure by Letters Patent, disclaim-
ing the mere details of the ornaments separately taken, is the
combination of the ornaments and moulding as applied,
according to the description, to the several parts and con-
figuration of stone substantially as represented and set forth.
